UNITED STATES PATENT OFFICE.

CHRISTIAN BODMER, OF NEW BRITAIN, CONNECTICUT, ASSIGNOR OF ONE-HALF TO JUSTUS A. TRAUT, OF NEW BRITAIN, CONNECTICUT.

BEVEL.

SPECIFICATION forming part of Letters Patent No. 711,464, dated October 21, 1902.

Application filed April 19, 1902. Serial No. 103,731. (No model.)

To all whom it may concern:

Be it known that I, CHRISTIAN BODMER, a citizen of the United States, residing in New Britain, in the county of Hartford and State 5 of Connecticut, have invented certain new and useful Improvements in Bevels, of which the following is a specification.

This invention relates to bevels; and it consists, substantially, in the improvements hereinafter particularly described.

The principal object of the invention is to provide a device or instrument of this kind which may be operated with accuracy and precision, and one also which is capable of 15 being successfully applied for use in a greater number of instances than is possible with many similar devices hitherto devised.

A further object of the invention is to provide a bevel possessing perfect balance or 20 equal distribution of the weight of the several parts or elements thereof, and one also possessing strength and durability and susceptible of being applied and adjusted with facility and effectiveness.

25 A further object is to provide a device or instrument of the character specified which is not easily distorted or sprung out of alinement at the working faces thereof, and one also which may be handled with great steadiness 30 in the various applications thereof to work of different kinds.

The above and additional objects are attained by means substantially such as are illustrated in the accompanying drawings, 35 wherein—

Figure 1 is a view in perspective of one form or embodiment of bevel-stock constructed substantially in accordance with my present improvements, and Fig. 2 is a longitudinal 40 sectional view thereof. Fig. 3 is a transverse sectional view on the line C C, Fig. 2, looking toward the left. Fig. 4 is a similar view to Fig. 1, taken from the opposite side of the bevel-stock with the position of the latter reversed end for end. Fig. 5 is a plan view of another form of stock for the bevel or instrument which may be employed in some instances. Fig. 6 is also a plan view representing the preferred form or embodiment of my 45 invention, the blade of the instrument being shown in an adjusted position with reference

to the stock and also broken off at the outer end. Fig. 7 is a longitudinal sectional view of Fig. 6, and Fig. 8 is a transverse sectional view of Fig. 6 on the line A A. Fig. 9 is an 55 enlarged transverse sectional view of bevel-stock employed in the preferred form or embodiment of device, said view being taken on the line B B, Fig. 6.

With general reference to the present subject of inventions it may be stated that accuracy or precision of operation is the end, aim, and effect of a well-constructed bevel, as is well known, yet many devices of this kind as hitherto devised have failed of attainment of such quality, due either to the unrefined character of the structure (especially in bevels made entirely of metal) or else to certain imperfections of organization of the parts or elements thereof. With a bevel the 60 weight of the parts or elements constituting the same should be equally balanced or distributed throughout, since the successful application of the device in use depends largely upon the stability thereof and the steadiness 65 with which it may be handled.

As illustrative of my present improvements, I have herein represented several forms or embodiments of a bevel possessing the qualities mentioned and also having other advantages, as will hereinafter appear. I construct the stock of a metal casting hollowed out on opposite sides to a suitable depth, (the working faces thereof being dressed or finished off in perfect alinement,) so as to leave a relatively thin and continuous web extending parallel with the broader sides of the stock and by means of which web the side portions (on which are the working faces of the stock) of the stock are connected and maintained 80 in proper rigid relationship throughout their entire length. As thus constructed the outer surfaces of the working or operative portions of the stock are finished off smoothly and evenly, and for the purposes of integrity and 85 strength of structure I make no other alteration of the casting from its original form, but preserve the "skin" of the metal on all other surface portions thereof intact or unbroken, more especially on both sides of the 90 connecting-web referred to, as well as at the inner angles of the stock, where weak points 95

are apt to exist. The particular location of the web permits a kerf or slot for the adjustable blade of the device to be formed in the stock by means of a saw, for instance, with-
 5 out requiring the saw to be passed through very much of the material of the stock and without removing any portion of the connecting-web for the purpose. In this way the integrity of the structure of the stock is largely
 10 preserved, and there is no tendency to distortion thereof, as might otherwise result from displacement or removal of a large proportion of the metal thereof. The said kerf or slot is formed in the side portions of the stock
 15 slightly to one side of and in a plane substantially parallel with the web, and the movable or adjustable blade is so supported as to be capable of being moved in and out entirely free of the web, so as not to wear away any
 20 of the said skin thereof. I employ suitable means for securing the blade in positions of adjustment, said means including an operating-rod extending lengthwise of the device, and the parts are so constructed and organ-
 25 ized as to give the best results in practice.

Reference being had to the accompanying drawings by the designating characters marked thereon, A, Figs. 1 to 4, inclusive, represents a bevel-stock embodying the es-
 30 sential features of my present improvements and which in some particulars is constructed substantially the same as the bevel-stock referred to in my pending application filed September 6, 1901, Serial No. 74,496. Said
 35 stock is constructed of a single casting hollowed out on opposite sides, as at 1 and 2, so as to form a relatively thin and continuous web 3, connecting the side portions 4 of the stock, said side portions being dressed off
 40 or finished on their outer surfaces, so as to constitute the working faces of said stock.

The skin of metal formed on the inner surfaces of the said side portions at the time of casting, as well as that formed on the op-
 45 posite surfaces of said web, is preserved un-
 broken or intact, and thus is rigidity and strength imparted to the structure, especially at the web and at the angles of intersection thereof with the said side portions. I form
 50 in the side portions, from one end of the stock, a kerf or slot 5 for the accommodation and working of the usual adjustable blade, the sides of said kerf or slot extending all the way through said side portions parallel with
 55 the web and terminating a suitable distance from the opposite end of the latter. The kerf or slot is formed by means of a saw or other implement, and it is apparent that com-
 paratively a small amount of metal is re-
 60 quired to be cut through or removed in the formation thereof and also that no part whatever of the said web 3 is removed for the purpose. As thus constructed any suitable means may be employed in connection with
 65 the stock for securing the blade in its different positions of adjustment; but preferably I construct the stock in a manner to receive

substantially the means for that purpose hereinafter specifically referred to in connec-
 70 tion with the embodiment of my improved bevel shown in Figs. 6 to 9, inclusive, such means being omitted in Figs. 1 to 4, inclusive, for the purpose of more clearly indicating the construction of the stock. Thus at one side of the open end of the kerf or slot 75 5 a boss 8 is formed on the stock, having therein a tapped or threaded opening 9, adapted to receive the threaded portion of a screw (such as hereinafter referred to) passing through the blade, and at the other side of 80 the said kerf or slot the stock is formed with a circular portion 10, having a boss provided with an enlarged opening 11 for the reception of the enlarged head of the screw, said boss being notched or cut out at coincident points 85 12 and 13 for permitting the passage of the effective end of an operating-rod, such as is hereinafter referred to in connection with Figs. 6 and 7. At a point in line with the coincident notches 12 and 13 the said circular portion is formed or provided with a bevelled or inclined surface 15, constituting an operative bearing-face for the said effective end of said rod, and in the opposite end portion of the stock of the bevel an opening 16 90 95 is formed, the sides of which constitute a bearing for the opposite end of the rod. In this particular embodiment of my improved bevel-stock the unremoved metal skin on the surfaces of the web 3 and the inner surfaces of the side portions of the stock is indicated at 18 in Fig. 3, and in order to prevent wearing away of this metal skin, such as might occur by frictional or rubbing contact of the movable blade with the adjacent 100 surface of the web, I so construct the kerf or slot 5 that the inner wall 20 thereof is projected from said web at either edge of the stock, so as to form raised bearing-surfaces for the blade at whatever position the latter 105 may be brought, said raised bearing-surfaces terminating at the open end of said kerf or slot in a similarly projected or raised flush seat 21 for the blade, said seat being integral with the web and constituting practically the 110 inner surface of the circular portion 11 of the stock hereinbefore referred to. It will thus be seen that the blade will be prevented from contact with the web in effecting adjustments thereof and also that the raised bearing-sur- 115 faces and seat for the blade will prevent any deflection of the latter toward the web by ac-
 120 cidental contact with external objects. With this particular embodiment of my improved bevel-stock provision is made for the blade 125 on one side of the central connecting-web 3, while on the opposite side of the latter pro-
 130 vision is also made for a rod for coöperation with the connecting devices between the blade and stock, and it will be seen that said stock possesses integrity and strength while being light in weight and also that the same is not apt to bend or warp in use, the alinement of the working face thereof being unimpaired

even under comparatively great stress which may be brought to bear thereon.

Reference being had to the preferred embodiment or form of my improved bevel, as shown in Figs. 5 to 9, inclusive, it may be stated that one of the principal purposes of the construction and organization of the elements thereof is to obtain a still better balance or more equal distribution of the weight of such elements throughout and also to derive a greatly-increased depth of stock on one side of the blade over that on the other side of said blade, whereby the bevel as a whole is susceptible of a greater number of applications in use than is possible with many bevels or similar instruments hitherto devised. Thus I form the stock B in this instance of a suitable casting of metal, which is hollowed out from one of the broader sides thereof to a considerable depth, as indicated at *m*, while from the opposite broader side the said stock is hollowed out at *n* to a comparatively limited depth only, the side portions 4^a 4^a of the stock being connected, as in Figs. 1 to 4, inclusive, by means of a similar relatively thin and practically continuous web 3^a , on both surfaces of which is retained the metal skin 18^a , formed thereon at the time of casting of the stock. In like manner the metal skin on the inner surfaces of the side portions 4^a 4^a at each side of the web, as well as that at the inner angles *o* of intersection of said side portions with said web, is also retained, as shown, so that the strength and rigidity of the structure are both increased to a marked degree. In this embodiment of my invention I construct the kerf or slot 5^a in the same manner as hereinbefore explained with reference to the structure shown in Figs. 1 to 4, and I also provide similar raised parallel bearing-surfaces 20^a 20^a for the adjustable blade D, as well as a similar flush or raised seat 21^a for said blade, the purpose of said raised surfaces and seat being the same as in the first embodiment. At the solid end of the stock corresponding to the open end 30, Fig. 7, of the kerf or slot 5^a I form a tapped or threaded opening 31 in the portion 32, which is considerably less in depth or thickness than the portion 33 on the opposite side of said kerf or slot, the said tapped or threaded opening being for the reception of the threaded portion 34 of a screw having an enlarged head 35, received in an enlarged circular opening 36 therefor, formed in the said solid portion 33 of the stock, the said screw-head having therethrough a transverse threaded opening 37, in which works the threaded portions of an operating-rod E, extending the full length of the stock between the side portions thereof of greatest depth, said rod having bearings in an opening 38 immediately adjacent to and coincident with the opening 37 in the screw-head, and a similar coinciding opening 39, formed in the opposite solid end portion 40 of the stock. The end 41 of the rod projects beyond the screw-

head and is conical or tapered in correspondence with the beveled or inclined surface portion 42, formed on the stock in line with the opening on said screw-head, said conical or tapered end of the rod being made to ride upon said beveled or inclined surface on proper manipulation of said rod to draw the divided portions of the stock together to tightly bear upon the sides of the blade, and thereby secure the latter to any position to which it may be brought or adjusted. In the present embodiment of my invention I dispense with the notch 12 of Figs. 1 to 4, the side of the enlarged opening 36 in the end of the stock being closed at such point to furnish an increased lateral bearing for the said screw-head to butt against, whereby the screw itself is not apt to become bent or distorted, and less strain is imposed upon the threads thereof. I may employ a bridge 45, connecting the side portions 4^a 4^a across the hollowed-out side of the stock of greatest depth, in which case I form a central bearing for rod E, as shown in dotted lines, Fig. 5, said bridge when employed lending additional strength and integrity to the structure, but being dispensed with in most instances. It will be seen from this embodiment of my invention that in virtue of the particular location of the operating-rod with reference to the blade of the instrument the weight of the elements is equally distributed throughout, the weight of said rod about counterbalancing the combined weight of the blade and the web 3^a , and thus is a great advantage derived in this class of devices. The construction and organization of the several elements of the device are also such that maximum wear and great integrity of structure are obtained, giving to the device the capacity or quality of accuracy and precision of working. By making the stock of greater depth or thickness on one side of the blade than on the other I am enabled to apply the device for setting off bevels from straight lines forming other than right angles with the surface on which the blade of the instrument is laid for marking, while that part of the said stock of least thickness or depth enables the device to be applied to objects of comparatively limited depth. It is apparent that I am not restricted to the precise details of construction and organization of elements herein illustrated and described, since variations therefrom may be made and still be within the scope of my invention.

Having described my invention, I claim—

1. A bevel-stock constructed of a metal casting hollowed out at the sides and comprising a relatively thin connecting-web between the side portions on which are formed the working faces of the stock, said side portions having a kerf for a blade formed therein with the walls of the kerf in planes outside of and parallel with the surfaces of said connecting-web, said kerf extending all the way through said side portions and being open at one end of the stock.

2. A bevel-stock constructed with side portions or working faces and an integral substantially continuous and relatively thin connecting-web, said side portions being formed 5 therein with a kerf for a blade with the walls of the kerf in planes outside of and parallel with the surfaces of said connecting-web, said kerf extending all the way through said side portions and being open at one end of the stock.
- 10 3. A bevel-stock constructed of a metal casting hollowed out at the sides and comprising a relatively thin connecting-web between the side portions on which are formed the working faces of the stock, said side portions having 15 a kerf for a blade formed therein with the walls of the kerf in planes outside of and parallel with the web, the surfaces of said web and the inner surfaces of the side portions having thereon a skin of metal.
- 20 4. A bevel-stock constructed with side portions or working faces and an integral connecting-web, said side portions having a kerf for a blade formed therein with the surface of both walls of the kerf in a plane outside of 25 and substantially parallel with the web.
5. A bevel-stock constructed of a metal casting having side portions or working faces, and an intermediate relatively thin connecting-web located nearer one surface of the 30 stock than the other, the parts of said side portions of greatest depth having a kerf for a blade formed therein with the walls of the kerf outside of and in planes parallel with said web, said kerf being open at one end of the stock.
- 35 6. A bevel-stock constructed of a metal casting having side portions or working faces, and an intermediate relatively thin connecting-web located nearer to one surface of the 40 stock than the other, the parts of the side portions of greatest depth having a kerf for a blade formed therein with the walls of the kerf outside of and in planes parallel with said web, and the surfaces of said web and 45 the inner surfaces of said side portions having thereon a skin of metal, and said kerf being open at one end of the stock.
7. A bevel-stock constructed at one end for the reception of connecting devices for a blade, and having side portions or working faces, and an intermediate connecting-web located nearer one surface of the stock than the other, the parts of said side portions of greatest depth having a kerf formed therein with the walls of the kerf outside of and in planes parallel with said web, and the end portions of the stock being formed beyond the kerf with bearings for a rod, said kerf being open at one end of the stock.
8. A bevel-stock constructed of a metal casting adapted at one end for the reception of connecting devices for a blade, and having side portions or working faces, and an intermediate connecting-web located nearer one surface of the stock than the other, the parts of 65 said side portions of greatest depth having a kerf formed therein with the walls of the kerf outside of and in planes parallel with said web, and the end portions of the stock being formed beyond the kerf with bearings for a 70 rod, the surfaces of the web and the inner surfaces of said side portions having thereon a skin of metal retained thereon, and the kerf being open at one end of the stock.
9. A bevel comprising a stock having side 75 portions or working surfaces, and a relatively thin connecting-web therefor located nearer one surface of the stock than the other, a movable blade working in a plane to one side of the web, securing devices for said blade 80 comprising an inclined surface on the stock and a screw having a head with a transverse opening thereon, and a rod coöperating with said devices located in bearings in the stock therefor on the same side of the web as the 85 blade.

CHRISTIAN BODMER.
